EARRING

William E. Lawson, Jr., and William E.
Lawson, Sr., Rahway, N. J.

Application February 5, 1948, Serial No. 6,378

2 Claims. (Cl. 63—14)

1

The invention relates to improvements in earrings, and particularly to improvements in perfumed earrings.

One of the objects of the invention is to provide an earring construction by which the earring ornament may be quickly and easily removed and replaced, or another ornament substituted for the one removed.

Another object of the invention is to provide a construction adapted to receive an absorbent pad or the like to carry perfume.

Still another object of the invention is to provide a construction which will conserve the perfume by preventing rapid evaporation, but which will permit the escape of sufficient fragrance.

A further object of the invention is to provide a very simple and inexpensive one-piece construction for removably securing the ornament in place and for securing the earring to the ear lobe.

Various other objects and advantages of the invention will be apparent from the following description when taken in connection with the accompanying drawings, in which:

Figure 1 is a side elevational view of the complete earring;

Figure 2 is a perspective view of the ornament removed;

Figure 3 is a front view of the earring with the ornament removed; and

Figure 4 is a vertical sectional view of the complete earring.

Referring to the drawings in more detail, numeral 1 indicates the ornament which, of course, may be of any preferred design, shape, size, color, and material. And with a number of different ornaments available, the wearer can select the particular ornament desired for the particular occasion or costume. And this preferred ornament can be quickly, easily, and securely mounted in place.

In the preferred construction illustrated the ornament will be provided near its base with an annular groove or depression 2, which is one of the elements for mounting the ornament, as will appear hereinafter.

The ornament as shown is provided with a pocket 3 for the reception of an absorbent pad 4, which will be saturated with the desired perfume. Of course, this pocket can be of any desired shape and size, but it is preferably a cylindrical pocket with a circular opening. This pocket or opening 3 also performs the additional function of assisting in securely fastening the ornament in place, as will appear hereinafter.

2

The rear face 5 of the ornament is preferably provided with one or more channels or vents 6, four of these being shown in the embodiment illustrated. These vents are preferably of very slight depth and width and are for the escape of the fragrance; the opening of the pocket being closed except for the vent or vents, as will later appear.

The body of the earring, herein termed the 10 clasp, includes a yoke 7 in one arm of which is threaded a clamping screw 8 having a rounded head 9.

The other arm of the yoke includes fingers 10, 10, and a closure tongue 11. It is to be noted 15 that these parts and the yoke are all preferably stamped from a single piece of metal. The fingers 10, 10 are appropriately curved and spaced in the form of a fork, and are under slight spring tension, so that when the ornament is inserted 20 the fingers will be spread slightly and then will snap clamp about the ornament, in the annular groove 2, thereby firmly holding the ornament in place. The ornament is removed in the same manner.

25 The tongue 11 performs several functions, it assists in holding the ornament in place, it assists in holding the earring on the ear lobe, it keeps the saturated cotton pad from coming in contact with the ear lobe, and by closing the 30 opening of the perfume pocket or chamber it conserves the perfume by preventing rapid evaporation both while the earrings are being worn and when they are put aside.

This tongue 11 has an annular peripheral flange 35 portion 12 and a central outwardly pressed or embossed portion 13; the flange portion and the embossed portion being connected by an annular beveled or inclined portion 14.

It will be understood, of course, that the closure 40 tongue is under a slight tension or spring pressure, so that when the selected ornament is snap clamped into position between the fingers 10, the embossed portion 13 snaps into the opening of the cylindrical perfume pocket 3, so that the 45 embossed portion with its annular inclined or beveled portion securely locks the ornament against movement.

It will also be noted, particularly by reference 50 to Figure 4, that the annular flange portion of the tongue together with the embossed portion and the beveled portion tightly seal the mouth of the perfume chamber, except for the small vents or channels 6 for the escape of the odor, whereby rapid evaporation is prevented both 55 while the earring is being worn and when it is

removed. And of course the tongue also keeps the perfume pad from coming into contact with the ear lobe. And the tongue also assists in firmly securing the earring to the ear, for the rounded head 9 of the clamping screw will force a portion of the ear lobe into the reverse embossing of the closure tongue.

From the foregoing description it will be apparent that we have devised a very simple and inexpensive construction by which an ornament can be quickly, easily, and securely attached to an earring clasp, and which can be removed just as easily and quickly, thereby permitting the wearer to select the ornament best suited for the costume or occasion. And the construction not only provides for the reception of a perfume-carrying pad, but also provides means for preventing rapid evaporation of the perfume, whether the earring is being worn or is idle, yet permitting the escape of sufficient fragrance.

Having fully described the invention, what we claim is:

1. An earring including an ornament and a clasp, said ornament provided with an open-ended pocket for carrying perfume, a groove provided on said ornament, and a channel on the ornament leading laterally from the open end of said pocket for venting the fragrance, spaced spring fingers carried by the clasp for engaging said groove, and a spring tongue carried by the clasp, a portion of said tongue shaped to close

said pocket except for said channel, and said portion being pressed by the tongue into such closing position.

2. An earring including an ornament and a clasp, said ornament provided with an open-ended pocket for carrying perfume, a groove provided on said ornament, spaced spring fingers carried by said clasp for engaging said groove, a spring tongue carried by the clasp, said tongue having an embossed portion, said embossed portion being pressed by said tongue into seating position in the open end of said pocket, and a clamping screw carried by the clasp, said screw cooperating with the reverse embossment for securely fastening the earring to the lobe of the ear.
